UNITED STATES PATENT OFFICE

164,853

CHILD'S COSTUMER

Sally Gross and Henrietta Stern, New York, N. Y.

Application June 25, 1951, Serial No. 15,653

Term of patent 7 years

(Cl. D33—8)

To all whom it may concern:

Be it known that we, Sally Gross and Henrietta Stern, both citizens of the United States of America, and residents of New York city, county of New York, and State of New York, have invented a new, original, and ornamental Design for a Child's Costumer, of which the following is a specification, reference being had to the accompanying drawing, forming part thereof, wherein:

We claim:

The ornamental design for a child's costumer, substantially as shown.

SALLY GROSS.
HENRIETTA STERN.
